UNITED STATES PATENT OFFICE

AURELIO AURELI, OF COGOLETO, ITALY, ASSIGNOR TO "ILVA" ALTI FORNI FONDERIE & ACCIAERIE D'ITALIA, OF GENOA, ITALY

CONTINUOUS-HEATING FURNACE

Application filed December 10, 1927, Serial No. 239,034, and in Italy October 6, 1927.

My present invention relates generally to furnaces, and has particular reference to a furnace through which a plurality of cylindrical articles, such as pipes, are to be continuously passed.

The furnace to which my invention has particularly reference is of the character which re-heats centrifugally cast tubes or pipes and is designed to have the pipes rolled or slid therethrough.

One of the general objects of the invention is to provide a furnace in which suitable conveyor mechanism has been arranged, whereby the passage of pipes through the furnace is expedited, simplified, and of a character uninjurious to the pipes regardless of their thickness or the heat to which they are subjected.

One of the salient features of my present invention resides in providing a furnace floor having a longitudinal slot in which an endless chain is arranged, a set of stakes being removably applicable through said slot into engagement with said chain, said stakes being adapted to project upwardly out of said slot into the spaces between the cylindrical articles.

A particular feature lies in providing the chain and stakes of such a character that the stakes may be variably positioned along the chain so as to accommodate a variety of differently sized pipes therebetween.

Another feature lies in so constructing the furnace floor that articles with enlarged ends (such as pipes having flanges at their ends) may be rolled through the furnace in full rolling contact with the floor, thereby minimizing any danger of deformation during the passage through the furnace.

Another feature resides in providing means for automatically causing the stakes to disassociate themselves from the chain after the passage of the chain and stakes through the furnace.

A still further feature lies in the provision of means for automatically guiding pipes of different lengths along two different paths after the same have left the furnace.

For the attainment of the foregoing objects and such other objects as may herein-

after appear or be pointed out, I have illustrated one form of the invention in the accompanying drawings wherein—

Figure 1 is a longitudinal cross-section through a furnace constructed in accordance with my present invention;

Figure 2 is a cross-sectional plan view of the same;

Figure 3 is a cross-sectional view taken substantially along the line *b*—*b* of Figure 2;

Figure 4 is a cross-sectional view taken substantially along the line *a*—*a* of Figure 2;

Figures 5 and 6 are enlarged detail views of the conveying mechanism at the outlet and inlet portions of the furnace respectively;

Figure 7 is a plan view of a portion of a conveyor chain constructed according to the present invention;

Figure 8 is a side view of Figure 7;

Figure 9 is a cross-sectional view of Figure 7; and

Figure 10 is a plan view of a portion of Figure 6.

Referring to the drawings, I will point out that the furnace is substantially tube-shaped, the inlet being at the left of Figures 1 and 2 and the outlet at the right thereof. Over the forward portion of the furnace a combustion chamber 1 is arranged, this chamber being provided with the burners 2 and the openings 3, the latter openings serving as a passage for the combustion gases to enter the furnace proper or hearth chamber 4. The products of combustion are allowed to leave the furnace through a series of vertical passages 5, the latter communicating with a pair of longitudinally arranged conduits 6 arranged beneath the furnace chamber 4. The conduits 6 join and communicate with a main exhaust conduit 7 leading to the stack.

Each of the passages 5 is provided with the usual slide which is conveniently operable from the outside of the furnace.

The bottom or floor 8 of the furnace proper is slightly inclined downwardly from the entrance to the exit thereof so as to facilitate the rolling through the furnace of the cylindrical articles for which it is designed. This flooring is preferably composed at the inlet

and exit openings of suitable fire brick or the like.

One of the features of my invention lies in providing the floor 8 with a set of longitudinal grooves 11 which are so cross-sectionally configured as to accommodate the enlarged ends of the cylindrical articles rolling through the furnace. In this way, the articles are suitably guided in their rolling movement and lateral displacement is thereby prevented. Of greater importance is the fact that the pipes or articles may roll through the furnace in full rolling contact with the floor 8, whereby even very thin cylindrical castings or the like, which are normally very liable to be deformed at high temperatures, may be successfully rolled through the furnace without injury thereto.

At 12 I have shown an inlet door, and at 20 13 an outlet door. These doors are preferably of sheet metal and are suitably hinged and provided with suitable counter-weights so that the opening and closing thereof will be facilitated with the cooperation of the incoming and outgoing articles. A set of small side doors 14 are also preferably provided, these doors having inspection holes or windows therein whereby the work within the furnace may be carefully observed and possible deviations of the articles promptly corrected.

The floor 8 is further provided with a pair of longitudinal slots 9 and 10 within which a pair of conveyor chains 15 are arranged. A 35 description of one of these slots and one of these chains will suffice for both.

The slots 9 and 10 are preferably lined with metallic U-shaped guides embedded within the refractory material of the floor 8. Referring to Figures 7-9, I will point out 40 that each chain comprises a set of spaced link members 16 and a set of intermediate link elements pivotally joining the members 16. Each link member 16 is in the form of a block having substantially flat bottom and top surfaces and being provided with a set 45 of equally spaced substantially vertical holes 17, whose purpose will be presently described. Each of the members 16 is also provided with a longitudinal groove 18 in its upper surface. Each intermediate link element comprises a 50 pair of opposed plates sandwiching the adjacent members 16 therebetween. These plates are pivotally connected to the members 16 by means of pins which extend through each member 16 and the plates sandwiching the same.

A number of stakes 19 and 20 are provided 60 for removable application through the slots 9 and 10 into selected engagement with the conveyor chains 15. Each stake is provided with a body portion 21 which merges into a pair of legs 22, the latter defining a portion of non-circular cross-section adapted to engage 65 within one of the grooves 18 to prevent rota-

tion of the stake. Each stake is also provided with a downwardly extending pin 23 suitably sized to engage within any one of the holes 17. Certain of the stakes, designated by the reference numeral 19, have the pins 23 arranged with their axes coincident with the axes of the stakes. Other of the stakes, designated by the reference numeral 20, have the pins 23 parallel to but offset from the axes of the stakes. The amount of the offsetting is something less than the interval between the holes 17, whereby a selected and judicious use of the stakes 19 and 20 permits of variable desired spacing as shown most clearly in Figure 5.

A pair of pulleys 24 and 25 are arranged at opposite ends of the furnace for guiding the conveyor chains. One of the pulleys 24 is shown in Figure 6 and is mounted upon a shaft 26. One of the pulleys 25 is shown in Figure 5 and is mounted upon a shaft 27. Each of the pulleys has a body portion 28 provided with a polygonal periphery 29, the latter defining a number of plane faces adapted to accommodate the under-surfaces of the link members 16. Sandwiching each body portion 28 are a pair of toothed discs 30, the teeth being so spaced and arranged as to engage between adjacent plates of the link elements on one side of the link members 16.

The shaft 27 of the pulleys 25 is extended as shown in Figure 2, and is driven, through a suitable chain of gears, by a motor 31. The speed of the chains may be varied within 100 desired limits by simply selecting the proper ratio of gears 32.

The rear pulleys 24 are mounted upon adjustable bearings 33, the latter being slidable upon guides 34 mounted upon the brickwork foundation 35. The tension of the conveyor chains may be adjusted by controlling the positions of the bearings 33, and this is preferably accomplished by means of screws 36 with which are associated the volute springs 37.

The conveyor chains, during the passage thereof from the pulleys 25 rearwardly to the pulleys 24, pass over flanged wheels or rollers 38 mounted upon the foundations 39 and positioned beneath the furnace proper.

The entrance door 12 is arranged between the rear pulleys 24 and is preferably provided with inspection windows or holes 40. At the front of the furnace, flush with the flooring 8, and preferably connected thereto, are a set of runways or guides 41 and 42. These runways are so constructed and arranged as to accomplish an automatic separation of certain longer articles from certain shorter ones. See for example Figures 1, 2, and 5. More particularly, the runway 41 consists of a pair of spaced rails adapted to guide articles of a length greater than the spacing of these rails. These rails preferably extend in a horizon-

130

tal direction as shown in Figure 5. The other runway 42 comprises a second set of rails arranged between the rails 41 and hence capable of guiding articles of a length greater than the spacing between the rails 42 but less than the spacing between the rails 41. The rails 42 preferably extend downwardly so as to guide the shorter articles below the longer ones as shown in Figure 5.

10 In order to facilitate the automatic withdrawal of the stakes 19 and 20 from the chains 13 after the latter have passed through the furnace, I provide a rod 43 in a transverse manner somewhat below the forward pulleys 25 (see Figures 1 and 5). As the stakes encounter the rod 43 they are automatically caused to fall into the funnel 44 from which they may ultimately be withdrawn and supplied to the entrance side of the furnace.

20 A motor 45 controls the burners 2.

I claim—

1. In a furnace through which is to be passed a plurality of cylindrical articles having each externally projecting parts at an end, 25 a furnace floor having a longitudinal groove accommodating the projecting parts of the cylindrical articles, whereby said articles may roll longitudinally through said furnace in full rolling contact with said floor.

30 2. In a furnace through which a cylindrical article is to be rolled, a plane furnace floor having a longitudinal slot, an endless conveyor chain in said slot and including link members having holes therein, a stake adapted to extend into said slot and project upwardly out of the same, and a pin on said stake removably engageable within any of said holes.

35 3. In a furnace through which a plurality of cylindrical articles are to be rolled, a plane furnace floor having a longitudinal slot, an endless conveyor chain in said slot and including link members having equally spaced holes therein, a plurality of stakes adapted to extend into said slot and to project upwardly out of the same into the spaces between said articles, and a pin on each stake removably engageable within any of said holes; certain of said pins having their axes coincident with 50 the axes of their stakes, other of said pins having their axes parallel to but offset from the axes of their stakes.

40 4. In a furnace through which a plurality of cylindrical articles are to be rolled, a plane furnace floor having a longitudinal slot, an endless conveyor chain in said slot and including link members having equally spaced holes therein, a plurality of stakes adapted to extend into said slot and to project upwardly out of the same into the spaces between said articles, and a pin on each stake removably engageable within any of said holes; certain of said pins having their axes parallel 55 to but offset from the axes of their stakes by

amounts less than the intervals between said holes.

5. In combination with a slotted furnace floor, a conveyor chain in said slot and including a link member having a longitudinal slot throughout its entire upper surface and a set of substantially vertical holes therein, a block with legs received in the groove of the link and a stake arranged in said block and removably applicable through said slot into engagement with said chain, and a pin engageable within any of said holes to prevent rotation of the stakes.

6. In combination with a slotted furnace floor, a conveyor chain in said slot and comprising a set of spaced link members each of which has a set of holes therethrough, a set of intermediate link elements pivotally joining said members, each of said elements comprising a pair of plates sandwiching the adjacent link members between them, a pin extending through each member and the plates sandwiching the same; and a stake removably applicable through said slot into engagement within one of said holes.

7. In combination with a linked conveyor chain comprising a set of spaced link members having substantially flat under surfaces, and a set of link elements pivotally joining said members and comprising plates sandwiching said members between them; a pulley comprising a body portion with a polygonal periphery, said periphery defining flat faces adapted to accommodate the under surfaces of said members, and a pair of toothed discs sandwiching said body portion, said teeth being so spaced and shaped as to enter the spaces between adjacent plates on opposite sides of said members.

8. In combination with a slotted furnace floor, a conveyor chain in said slot, a pair of pulleys for said chain at opposite ends of said floor, whereby the chain will move through said slot and thence around one of said pulleys, a set of stakes removably associated at spaced intervals with the portion of the chain in said slot, said stakes extending upwardly through said slot, and means for dislocating said stakes after they leave said slot, said means comprising a transverse obstruction encounterable by said stakes as the chain passes around said pulley.

9. In a furnace through which a set of cylindrical articles are to be rolled, a furnace floor, an exit door, and a set of runways flush with the floor at said door, one of said runways comprising a pair of spaced rails adapted to guide articles of a length greater than said spacing, the other of said runways comprising a pair of rails between said first-named pair and adapted to guide articles of a length greater than said last-mentioned spacing and less than said first-mentioned spacing.

10. In a furnace through which a set of

cylindrical articles are to be rolled, a furnace floor, an exit door, and a set of runways flush with the floor at said door, one of said runways comprising a pair of spaced rails adapted to guide articles of a length greater than said spacing, the other of said runways comprising a pair of rails between said first-named pair and adapted to guide articles of a length greater than said last-mentioned spacing and less than said first-mentioned spacing; the intermediate pair of rails extending downwardly to guide the shorter articles below the longer ones.

In testimony whereof I have hereunto
15 signed my name.

AURELIO AURELLI.
